(57) **CLAIM**

The ornamental design for a medical diagnostic tool as shown and described.

DESCRIPTION

FIG. 1 is a perspective view of the medical diagnostic tool showing my new design.

FIG. 2 is a left side view thereof;

FIG. 3 is right side view thereof;

FIG. 4 is back view thereof;

FIG. 5 is a front view thereof;

FIG. 6 is a top view thereof; and,

FIG. 7 is a bottom view thereof.

The horizontal lines shown on the surface of the claimed design in FIGS. 1-7 illustrate shading and form no part of the claimed design.

The dashed lines shown on the hands and the syringe of FIG. 1 form no part of the claimed design.

The dashed lines shown on the chamber of FIG. 1 represent background and form no part of the claimed design.

1 Claim, 7 Drawing Sheets
